UNITED STATES PATENT OFFICE

2,614,620

TOP BURNER FOR GAS RANGES

John E. Chambers, Shelbyville, Ind., assignor to
 Chambers Corporation, a corporation of Indiana

Application October 18, 1948, Serial No. 55,092

8 Claims. (Cl. 158—116)

1

This invention relates to a top burner for gas ranges, and particularly to a chimney-type burner having a plurality of chimneys fed with gas from a common source.

In chimney-type burners previously known, a hollow base is provided with a plurality of individual chimneys projecting upwardly from the hollow base, as shown in the patent to Phares, No. 2,144,894, for example. In such burners the burner openings are so high above the flash port that it is necessary to provide a series of lead-up ports along the wall of one of the chimneys adjacent the flash port so that the flame from the flash port may ignite gas issuing from the lead-up ports and then follow the lead-up ports up the chimney wall to ignite gas issuing from the burner openings. In brief, in such burners the flame must be brought from the flash port to the burner openings of the chimney. The flame from the burner openings of the chimney having the lead-up ports then ignites the gas issuing from the burner openings of the other chimneys.

It is difficult and adds to the cost to provide proper lead-up ports in the chimney wall. Additionally, the lead-up ports interfere with the combustion at the top burner openings. Also, they tend to become clogged in use and in time fail to function, thereby becoming a hazard. In consequence, it is necessary to clean these prior art chimney-type burners frequently to insure that the lead-up ports are open to permit the free passage of the ignitable gas and air mixture.

In accordance with the present invention the burner is so shaped that the flame from the flash port will run up the outside walls of two chimneys and ignite the gas issuing from these chimney openings, thus eliminating the lead-up ports and at the same time introducing a safety factor. The shape of the interior of the burner regulates the flow of the gas-air mixture within the burner so that a portion of this flow will be relatively accelerated and be enabled to emerge from the flash port, run through the flash tube to the pilot light and be ignited, flash back, and run up the outside walls of the two chimneys adjacent the flash port and reach the burner openings simultaneously with the emergence of the gas-air mixture from the burner openings, thus introducing a further safety factor.

Each chimney of the burner of the present invention is provided with a plurality of radial fins extending outwardly from and vertically of the chimney wall to insure that the drip ring will be properly positioned so as not to interfere with or choke off the supply of secondary air to the

2

burner. These radial fins also serve as wind breakers to help shield the flame which flashes back to the burner openings from gusts of wind, such as are caused by slamming doors, which might otherwise put out the flame.

The burner is shaped so as to be narrow at its base and massive at its top to provide a maximum heat radiation from the heated burner at the top, adjacent the bottom of the cooking vessel to be heated. A further advantage flowing from a burner of this construction is that a minimum of heat is dissipated along the base of the burner to the front of the range, where the presence of heat is objectionable.

The structure by which the above advantages are attained will be described in the following specification, taken in conjunction with the accompanying drawings, in which:

Fig. 1 is a fragmentary perspective view of a gas range, indicating the relative position of the top burners which comprise the subject matter of the present invention;

Fig. 2 is a top plan view of a top burner embodying the invention, showing the gas line and a portion of the flash tube;

Fig. 3 is a cross sectional view, taken along the line 3—3 of Fig. 1, showing the top burner and the associated gas well structure;

Fig. 4 is an end elevation, looking in the direction of the arrows along the line 4—4 of Fig. 2;

Fig. 5 is a top plan view of the top burner and associated gas well structure, with a portion of the burner broken away to show the wall structure;

Fig. 6 is a longitudinal sectional view, taken generally along the line 6—6 of Fig. 2, but showing fragmentary portions of the pilot burner and flash tube; and

Fig. 7 is a cross sectional view, taken along the line 7—7 of Fig. 6.

In the drawings, the reference numeral 2 indicates a gas range having a plurality of top burners 3 spaced from a pilot burner 4. The present invention resides entirely in top burner 3 and its associated structure. Accordingly, the description will be substantially limited to these parts without going into detail as to the structure of the range.

Pilot burner 4, which is conventional, comprises a pipe 5 leading from a source of gas and terminating adjacent one end of each of a plurality of flash tubes 6. Each flash tube 6 has its other end terminating near one top burner 3. Pipe 5 is open to the atmosphere at its end adjacent flash tubes 6 and the gas is ignited at

the open end of the pipe. The amount of gas flowing through pipe 5 is regulated so that a small flame burns constantly at this point. In operation of any top burner 3, gas fed through the flash tube of the particular burner is ignited by the pilot light and the flame flashes back through the flash tube, strikes against the wall of the burner, and runs up the wall to ignite gas issuing from the burner openings.

Top burner 3 comprises a hollow base 7 having a plurality of integral chimneys 8 extending upwardly therefrom. Although four chimneys are shown in the burner illustrated in the drawings, it will be obvious that this number may be varied. Chimneys 8 are interconnected by means of an intermediate hollow housing 7' which communicates directly with hollow base 7. Housing 7' and all chimneys 8 have a common outer wall 9 which constitutes the perimeter of the burner. A partially restricted vertical opening 10 leads from intermediate housing 7' to the interior of each chimney 8 so that the flow of gas from hollow base 7 into chimneys 8 is somewhat impeded.

A series of burner openings 11 extends around the perimeter of each chimney adjacent its top. Each chimney is also provided on its outer wall with a pair of radial fins 12 which extend vertically throughout the length of the chimney. Fins 12 of each pair are spaced apart a distance of approximately 90° for a purpose hereinafter described.

Hollow base 7 is comparatively narrow, as seen in Figs. 4 and 7, and side walls 13 and 14 are curved outwardly and upwardly to form a wide bottom for chimneys 8. This construction concentrates the mass of top burner 3 at its top, thereby causing the maximum heat radiation of the heated burner to take place at the top, adjacent the cooking vessel to be heated.

Chimneys 8, in the embodiment of the invention illustrated, are arranged in pairs on opposite sides of intermediate housing 7'. Wall 9 is curved inwardly between adjacent chimneys, and base 7 extends beyond the portion of wall 9 which joins the two outermost chimneys 8. A flash port 15 extends through the top wall 16 of hollow base 7 between the two outermost chimneys near the point where wall 9 merges with the top of base 7. Flash tube 6 has a depending lug 17 near its end remote from pilot burner 4, and this lug fits into flash port 15. A bore 18 extends vertically through lug 17 and the adjacent wall of flash tube 6 so that gas will flow from hollow base 7, through bore 18, and through flash tube 6 to the pilot light.

The opposite end of base 7 merges into a goose neck pipe 19 through which a mixture of gas and air is fed into the burner. A coupling 20 threaded into an inlet port 21 in the end of goose neck pipe 19 connects it to a gas line 22. The flow of gas into pipe 19 is controlled by a conventional valve (not shown). Goose neck pipe 19 has an air opening 23, as seen in Fig. 2, the effective area of which is controlled by a flat plate 24 pivoted to pipe 19 by means of a screw 25. Plate 24 may be fixed in any adjusted position, relative to air opening 23, by tightening screw 25.

The cross sectional area of goose neck pipe 19 increases gradually from the inlet end to the point where it merges with hollow base 7. Base 7 is of approximately uniform cross sectional area throughout its length so as to form an unobstructed passageway for gas from pipe 19 to 75

flash port 15. This causes the gas to fill hollow base 7 before it starts to fill intermediate hollow housing 7'. The gas flows upwardly into housing 7' at the same time that it flows forwardly 5 through bore 18 to flash tube 6.

Restricted openings 10 leading from intermediate housing 7' into each chimney 8 offer just enough obstruction to the flow of gas that the initial flow of gas to flash tube 6 has time to reach the pilot light, be ignited, and flash back to flash port 15 as chimneys 8 are filled with gas. The gas begins to flow through burner openings 11 at approximately the same time that the flame flashes at flash port 15. This 10 flame strikes wall 9 adjacent flash port 15 between the projecting walls of the two outermost chimneys, and runs up the wall to burner openings 11, being guided in that direction by the projecting walls of the chimneys which also 15 shield the flame from gusts of wind. The flame running up the wall strikes the gas issuing from burner openings 11 of the two outermost chimneys and ignites it. The flame from the two outermost chimneys ignites the gas issuing from 20 the other chimneys. There is only a very short interval of time between the flash of flame at flash port 15 and the ignition of all chimneys of the burner.

Each burner 3 is encased in a gas well 26 having a flanged top 27 secured to the underside of the top wall 28 of range 2 by means of screws 29. A drip ring 30, apertured as indicated at 31 to fit around chimneys 8, is positioned in each well 26 with its upper flange resting on a ledge 35 of top wall 28. A top burner grate 34, of any suitable construction, is positioned over drip ring 30. The primary purpose of drip ring 30 is to serve as a catch-all to protect the bottom of gas well 26 from anything that may spill or boil over from a cooking vessel on the range.

In addition to the primary air supplied through air opening 23, each burner requires an additional supply of secondary air adjacent its burner openings for efficient operation. In order to insure an adequate supply of secondary air around each chimney the aperture in the base of drip ring 30 is shaped to conform to the clover-leaf shape of burner 3. The inner edges of the aperture fit closely against radial fins 12. The provision of two fins spaced approximately 90° apart on each chimney makes it impossible for the inner edge of drip ring 30 to hug any portion of the periphery of any chimney 8 so closely as to choke off the secondary air supply. Fins 12 maintain the inner edges of drip ring 30 at a uniform distance from wall 9 and thereby insure an adequate supply of secondary air around each chimney.

Drip ring 30 has an upstanding flange 35 which extends above the level of burner openings 11 and provides additional protection against wind so that the flame from the burner will not be blown out by gusts of wind caused by the slamming of a door or otherwise.

Although I have described a preferred embodiment of my invention in considerable detail, it will be understood that the description thereof is intended to be illustrative, rather than restrictive, as many details may be modified or changed without departing from the spirit or scope of the invention. Accordingly, I do not desire to be limited to the exact structure described.

I claim:

1. A top burner for gas ranges comprising a

hollow base having a horizontally disposed top wall, an inlet port for admission of gas to one end of said base, a flash port adjacent the remote end of said base, said base forming an unobstructed passageway for the flow of gas to said flash port, a hollow intermediate housing above the top wall of said base in direct communication therewith, and a plurality of chimneys having burner openings above said intermediate housing, said chimneys being interconnected by said intermediate housing.

2. A top burner for gas ranges comprising a narrow hollow base having a horizontally disposed top wall, a gas inlet at one end of said base and a flash port at the other, said hollow base forming an unobstructed passageway for the flow of gas from said inlet to said flash port, a plurality of chimneys extending upwardly above said top wall from each side of said hollow base, said chimneys having burner openings adjacent the top thereof, the outermost chimneys on each side of said base being adjacent to and on opposite sides of said flash port and the portions of outer walls of the said chimneys closest to said flash port being curved inwardly towards each other above said flash port, thereby forming a recessed passageway between said chimneys and adjacent said flash port to guide a flame from said flash port to said burner openings.

3. A top burner for gas ranges comprising a hollow base having a horizontally disposed top wall and a vertically disposed outer wall rising from said top wall, an inlet port for admission of gas at one end of said base, a flash port at the opposite end of said base extending through a portion of said top wall, said hollow base forming an unobstructed passageway for gas from said inlet port to said flash port, a plurality of pairs of chimneys extending upwardly from said base, the chimneys of each pair being positioned adjacent opposite sides of said base with the outermost pair of chimneys being positioned on opposite sides of said flash port, each of said chimneys having imperforate lateral walls and a plurality of burner openings adjacent its top, the outer wall of said burner being curved inwardly between said two outermost chimneys to form a recessed passageway extending vertically from said top wall portion adjacent said flash port to a region adjacent said burner openings, and means forming vertically disposed, partially restricted passageways for gas leading from said hollow base to each of said chimneys.

4. A top burner for gas ranges comprising a hollow base having a horizontally disposed top wall and a vertically disposed outer wall rising from said top wall, an inlet port for admission of gas at one end of said base, a flash port at the opposite end of said base extending through a portion of said top wall, said hollow base being of uniform cross section and forming an unobstructed passageway for gas from said inlet port to said flash port, four chimneys of substantially cylindrical shape extending upwardly from said base, said chimneys being arranged in pairs, the chimneys of each pair being positioned adjacent opposite sides of said base with the outermost pair of chimneys being positioned on opposite sides of said flash port, each of said chimneys having imperforate lateral walls and a plurality of burner openings adjacent its top, the outer wall of said burner being curved inwardly between said two outermost chimneys to form a recessed passageway extending vertically from said top wall portion adjacent said flash port to

a region adjacent said burner openings whereby a flame issuing from said flash port will be directed upwardly to the area adjacent said burner openings, and means forming vertically disposed, partially restricted passageways for gas leading from said hollow base to each of said chimneys.

5. A top burner for gas ranges comprising a hollow base having a horizontally disposed top wall, an inlet port for admission of gas at one end of said base, a flash port at the opposite end of said base extending through a portion of said top wall, said hollow base forming an unobstructed passageway for gas from said inlet port to said flash port, a plurality of pairs of chimneys extending upwardly from said base, the chimneys of each pair being positioned adjacent opposite sides of said base with the outermost pair of chimneys being positioned on opposite sides of said flash port, each of said chimneys having imperforate lateral walls and a plurality of burner openings adjacent its top, a hollow intermediate housing above said base and communicating directly with said base, and means forming vertically disposed, partially restricted passageways for gas leading from said intermediate housing to each of said chimneys, the outer wall of said intermediate housing being curved inwardly between said two outermost chimneys to form a recessed passageway close to said flash port, and vertically disposed fins projecting outwardly from said two outermost chimneys adjacent said flash port, said fins co-operating with said recessed passageway to guide a flame from said flash port to said burner openings.

6. A top burner for gas ranges comprising a hollow base having a horizontally disposed top wall and a vertically disposed wall rising from said top wall, an inlet port for admission of gas at one end of said burner, a flash port extending through a portion of said top wall at the opposite end of said burner, said hollow base providing an unobstructed passageway for gas from said inlet port to said flash port, a plurality of chimneys extending upwardly from said hollow base, the said flash port being adjacent the bottoms and intermediate a pair of said chimneys, each of said chimneys being laterally imperforate and having a plurality of burner openings adjacent its top, the outer walls of said pair of chimneys being curved inwardly above said flash port and joined by said vertically disposed wall, thereby forming a recessed passageway between said chimneys extending from said top wall portion adjacent said flash port to a region adjacent said burner openings to guide a flame from said flash port to said burner openings, and means forming a vertically disposed, partially restricted passageway for gas leading from said hollow base to each of said chimneys, the degree of restriction being such that when gas is admitted to said hollow base through said inlet port, a portion of said gas will flow to said flash port, be ignited and have its flame reach the burner openings at approximately the same time other portions of the gas passing into said chimneys begins flowing through said burner openings into the atmosphere.

7. A top burner for gas ranges comprising a hollow base having a horizontally disposed top wall and a vertically disposed wall rising from said top wall, an inlet port for admission of gas at one end of said burner, a flash port extending through a portion of said top wall at the opposite end of said burner, said hollow base pro-

viding an unobstructed passageway for gas from said inlet port to said flash port, a plurality of chimneys extending upwardly from said hollow base, the said flash port being adjacent the bottoms and intermediate a pair of said chimneys, each of said chimneys being laterally imperforate and having a plurality of burner openings adjacent its top, the outer walls of said pair of chimneys being curved inwardly above said flash port and joined by said vertically disposed wall, thereby forming a recessed passageway between said chimneys extending from said top wall portion adjacent said flash port to a region adjacent said flash port to said burner openings, and means forming a vertically disposed, partially restricted passageway for gas leading from said hollow base to each of said chimneys.

8. A top burner for gas ranges comprising a narrow hollow base having a horizontally disposed top wall and a vertically disposed wall rising from said top wall, a gas inlet at one end of said base and a flash port at the other extending through a portion of said top wall, said hollow base forming an unobstructed passageway for the flow of gas from said inlet to said flash port, a plurality of chimneys extending upwardly from each side of said hollow base, said chimneys having burner openings adjacent the

15 top thereof, the outermost chimneys on each side of said base being adjacent to and on opposite sides of said flash port and the outer walls of said chimneys being imperforate and curved inwardly and joined by said vertically disposed wall to form a recessed passageway between said chimneys extending from said top wall portion adjacent said flash port to a region adjacent said burner openings, said recessed passageway being effective to guide a flame from said flash port to said burner openings.
